UNITED STATES PATENT OFFICE.

MATHIAS THURSTON, OF STRYKER, OHIO, ASSIGNOR TO THE NEY MANUFACTURING COMPANY, OF CANTON, OHIO, A CORPORATION OF OHIO.

HAY-CARRIER.

No. 899,688.

Specification of Letters Patent.

Patented Sept. 29, 1908.

Application filed March 4, 1908. Serial No. 419,138.

To all whom it may concern:

Be it known that I, MATHIAS THURSTON, a citizen of the United States, residing at Stryker, in the county of Williams and State of Ohio, have invented certain new and useful Improvements in Hay-Carriers, of which the following is a specification.

My invention relates to the class of hay carriers in which the carrier proper is adapted to move back and forth upon a track or way and the elevating rope leads from the carrier in a line transverse to the track or way.

The objects of the present invention are as follows: First, to provide a carrier wherein a cross-draft is applied, and second to provide means for locking the elevating rope and the load carried thereby at any point of elevation of the load or the instant the pull upon the elevating rope is released. I attain these main objects and other minor objects, by the mechanism illustrated in the accompanying drawings, in which—

Figure 1 is a side view of the carrier mounted upon the track or way and showing the elevating rope properly threaded in the carrier. Fig. 2 is an elevation of the carrier taken from the same point of view as Fig. 1, but in this figure the side of the carrier has been removed and parts are shown in section. Fig. 3 is an elevation of the carrier mounted upon the track or way, said view being taken at right angles to the line of view in Figs. 1 and 2. Fig. 4 is a cross-section on line 4—4, Fig. 1. Fig. 5 is an elevation of the carrier mounted upon the track or way, showing the carrier threaded with the elevating rope, the same sustaining the load, the rope being locked and the side of the carrier frame removed. Fig. 6 is a vertical section on line 6—6, in Fig. 5. Fig. 7 is a vertical section upon the line 7—7, in Fig. 1.

Similar numerals of reference indicate corresponding parts in all the figures of the drawings.

In the accompanying drawings, 1 and 2 represent the spaced side members of the lower frame section, which are held in proper spaced relationship with reference to each other by interposed members hereinafter described and tied together by suitable clamping bolts. The side members are also secured in proper spaced relationship with reference to each other, by the connected track frame 3, which is connected to the lower

frame members 1 and 2 by suitable clamping bolts 4. The parts just above described are common in hay elevators of this class, except as to their detailed construction hereinafter described.

The side members 1 and 2 are provided with the lugs 5, upon which lugs are pivotally mounted the main pulley carrying levers, which levers consist of the upper portions 6 and the lower portions 7, said portions 6 and 7 being located at an angle to each other as best illustrated in Fig. 5. For the purpose of providing sufficient room, between the lower frame members 1 and 2, to receive the main pulley carrying levers and at the same time providing for bringing the members near together, beyond the points where the levers are located, said side members are chambered as best illustrated in Figs. 4 and 6.

The main pulley 8 is mounted upon the axle 9 or more specifically upon the roller bearings 10 shown in the drawings, which axle extends through the curved slots 12, said axle being carried by the pivoted levers consisting of the parts 6 and 7. Below the main pulley 8 is located the rope grip actuating lever 13 which lever is provided with the integral angled portions 14, which extend upward or toward the pulley 8 and their top or upper ends provided with the recesses 15, into which recesses the lower ends of the portions 7 of the levers are seated. To the upward extended angled portions 14 are pivotally connected the links 16, which links are pivotally connected to the movable rope grip 17.

For the purpose of holding the rope-grip 17 in proper relationship with reference to the fixed rope-grip 18, the suspending links 19 are provided, which links are pivotally connected to the movable rope-grip 17, at their bottom or lower ends, their top or upper ends pivotally connected to the side members 1 and 2 of the lower frame. The fixed rope-grip 18 is held in fixed relationship with reference to the frame members 1 and 2 by means of suitable clamping bolts 20 or their equivalents. Below the rope grips 17 and 18 are located the rope guide rollers 21, which rollers are for the purpose of holding that portion of the rope 22 between the upper surfaces of the rollers 21 and the bottom or lower ends of the rope grips 17 and 18 in substantial alinement with the clamping faces of said rope-grips, by which arrange-

ment the entire length of the gripping surfaces of the rope grips can be better utilized to grip and hold the rope.

The elevating rope 22 is secured at one end to the clevis 23 or its equivalent, which clevis is attached to the catch 26 hereinafter described. In use the rope is threaded through the sling pulley blocks 24 or any elevating head commonly used in hay elevators of this class. The rope is extended or threaded between the rollers 21, the rope-grips 17 and 18, and thence over the pulley 8 passing the roller 25 from whence it is extended any desired distance to the point where the hitch is made to lift the load.

For the purpose of temporarily holding the lever 13 in an elevated position or in the position illustrated in Figs. 1 and 2, said lever is provided with the pivoted catch 26, which catch is provided at its upper free end with the hook 27 which hook is adapted to engage the cross rib or bar 28 said cross-rib or bar being connected to the frame members 1 and 2 in any convenient and well known manner.

For the purpose of preventing the catch from becoming disengaged from the rib or bar 28 by the weight of the sling or other device or devices used in elevating loads of hay or other material, the spring 29 is provided, which spring is so tensioned that it will hold the hooked end of the catch 26 in engagement with the rib or bar 28 and for the purpose of adjusting the tension of the spring the adjusting screw 30 is provided, which adjusting screw is extended through a screw threaded aperture in the spring housing 31. The tension of the spring 29 is only for the purpose of holding the catch 26 in engagement with the rib 28 during the time the sling is unloaded or empty, but when a load is elevated the pull will be sufficient to overcome the tension of the spring and disengage the catch 26 for the purpose hereinafter described.

It will be understood that when the lever 13 is in the position illustrated in Figs. 1 and 2 the right angled portions 14 will be held in position to release the elevating rope, owing to the fact that the rope grip 17, is moved away from said rope and the stationary grip 18 by means of the links 16, at which time the elevating rope is free to move between the grips 17 and 18. The elevating rope 22 is illustrated as shown over the pulley 8 and when a pull is given to the elevating rope the pulley will move or be carried in the direction of the pull of the rope, or in other words in the direction of the movement of the elevating rope for a limited distance, which movement is permitted by connecting the axle 9 to the portions 6 of the rock levers, which rock levers consist of the portions 6 and 7. Said levers are pivotally attached to the frame members 1 and 2 respectively

by which arrangement, a limited oscillating movement of the levers is permitted, which in turn permits the pulley 8 to move back and forth for a limited distance, following the movement of the elevating rope. When the lever 13 is pulled or held down by the weight of the load or held in position illustrated in Fig. 5, the rope grip 17 will be moved into position to clamp the elevating rope between said rope grip 17 and the stationary grip 18, at which time there can be no downward movement of the load; but when a pull is given to the elevating rope of sufficient degree to elevate the load the pulley 8 will be moved into the position illustrated in dotted lines Fig. 5, which moves the lower portions 7 of the pulley carrying levers toward the stationary rope grip 18 and moves the rope grip 17 away from said stationary rope grip 18, by reason of the movement of the lower ends of the portion 7 of the pulley carrying levers, said portions being seated in the recesses 15, thereby moving the angled portion 14 with the portion 7 of the main pulley carrying levers.

It will be understood that the same initial pull which releases the hook 27 from the bar 28 will also move the pulley 8 into the position shown in dotted lines in Fig. 5, which will, by means of the connecting mechanism, release the grips from the elevating rope and if this pull is continued the said grips will remain unlocked but if at any time slack is given to the elevating rope 22 the pulleys 8 will move into the position shown in full lines in Fig. 5, and thus permit the downward pull upon the lever 13, by reason of the weight of the load, to again lock the grips upon the rope.

It will be understood that the outer end of the lever 13 must be elevated when the angled portions 14 are moved as just above described, and in order that this movement can be brought about the force exerted upon the pulley 8 when the pull is given to the elevating rope must be greater than the down pull of the rope upon the lever 13. This action takes place by reason of the difference in the down pull of the rope upon the lever 13, and the pull of the rope upon the pulley 8. The catch 26 will be held out of engagement with the bar or rib 28 during the time a load is being elevated or when the elevating rope is slackened by reason of connecting said elevating rope to the pivoted catch 26, which catch is held in a position to hold its hooked end away from and out of engagement with the rib or bar 28.

It will be understood that the instant the elevating rope is given any slack the levers carrying said pulley will rock upon their pivotal points, which rocking movement throws the outer or free end of the lever 13, thereby bringing the rope grip 17 into action by means of the links or straps 16, thereby

clamping the rope and holding the load against downward movement.

It will be understood that in some instances it may be desired to lower the load after it has been elevated and in order that the rope may not be clamped when slack is given to it, the lever 13 is held in elevation by means of the auxiliary pivoted catch 32, which catch is provided with the lower hooked end 33, which hooked end engages the notch 34 formed in one side of the lever 13. The auxiliary catch 32 is provided with the right angled integral eye-bar 35, which right angled integral eye-bar is pivotally connected to one 15 of the side members of the lower frame.

For the purpose of preventing any accidental displacement of the auxiliary catch 32 it is extended a short distance above the eye-bar 35 and a spring 36 is located against said 20 upper portion, which spring is located in the socket 37 formed in the inner side of one of the carrier frame sections, said spring being for the purpose of normally holding the auxiliary catch 32 out of engagement with the lever 13. When it is desired to temporarily lock the lever 13 in its elevated position and release the rope grip and free the elevating rope, the eye-bar 35 is moved downward at its outer end by a cord 33^a or its equivalent 25 30 extended downward a sufficient distance to be grasped by the hand of the operator, which downward movement throws the lower end of the auxiliary catch 32 into position to seat the hook 33 in the recess 34. The upper frame 3 carries the usual traveling wheels 38, which are fitted to the track rails 39, and of course travel upon said track rails.

For the purpose of preventing any accidental derailment of the carrier proper during the time it is traveling back and forth upon the track rails, the upper frame 3 is provided with the cross-bars 40, which cross-bars are provided with upward extended 40 45 flanges 41 located below the flanges of the traveling wheels 38, and extending beyond said flanges and under the lower flanges of the track. If for any reason the carrier is swung greatly out of its proper position and 50 55 into an angle to a vertical line or in case the said carrier is jolted or thrown upward so as to cause the traveling wheels 38 to be lifted from the track, the said flanges 41 will come in contact with the lower flanges of the track and effectually prevent derailment.

For the purpose of providing room for the heads of the track suspending device 42, the flanges 41 are spaced as illustrated in Figs. 1, 2 and 5.

Having fully described my invention what I claim as new and desire to secure by Letters Patent, is—

1. In a hay carrier of the class described, a carrier frame adapted to move upon a track or way, said frame provided with pivoted

levers, a main pulley mounted upon an axle and the axle carried by the pivoted levers, a lever pivoted to the carrier frame below the main pulley and below the levers carrying said main pulley, a pivoted catch secured to 70 said last mentioned lever, an elevating rope secured to said catch, said elevating rope located over the main pulley and means for actuating the lever provided with the pivoted catch and means for gripping the elevating rope, substantially as and for the purpose specified.

2. In a hay carrier of the class described, a carrier frame adapted to move upon a track or way, rocking levers pivoted to said frame, 80 a main pulley carried by said rocking levers and adapted to rock with said rocking levers, a lever pivoted to said frame, an elevating rope operatively connected at one of its ends to said last mentioned lever, said elevating 85 rope located over the main pulley and adapted to rock the pulley and actuate the lever, substantially as and for the purpose specified.

3. In a hay carrier of the class described, a frame, a pulley carried by said frame, rocking 90 levers upon which said pulley is mounted, a lever located below the rocking levers carrying the main pulley, an elevating rope extended from the free end of the last mentioned lever and over the pulley carried by 95 the rocking levers and means for actuating the lever located below the rocking levers carrying the main pulley by the pull of the elevating rope, substantially as and for the purpose specified.

4. In a hay carrier of the class described, a frame adapted to move upon a track or way, rocking members pivoted to said frame, a lever located below the rocking members, said rocking members and lever operatively 105 connected together, a pivoted catch carried by the lever, an elevating rope attached at one of its ends to said pivoted catch, a main pulley carried by the rocking members, and adapted to rock with said members and the 110 elevating rope located over and upon said main pulley, a movable rope clamp and a fixed rope clamp and mean for actuating the movable rope clamp, substantially as and for the purpose specified.

5. In a hay carrier of the class described, a frame adapted to travel upon a track or way, a main pulley mounted upon an axle parallel with the track or way, rock levers pivotally attached to the frame and the main pulley 120 carried by said rock lever, a lever located below the rock levers and the main pulley, said lever pivotally connected to the frame, a pivoted catch carried by said last mentioned lever, an elevating rope connected to said 125 pivoted catch and extended downward and thence upward and over the main pulley, a stationary rope grip and a movable rope grip and means for moving the rope grip connected to the lever located below the levers carrying 130

the main pulley, substantially as and for the purpose specified.

6. In a hay carrier of the class described, a frame adapted to travel upon a track or way, 5 rocking levers pivotally attached to the frame, a main pulley carried by the rock lever, said pulley adapted to rock in unison with the rock levers, a lever located below said rock levers, an elevating rope operatively connected to said lever and the rock levers operatively connected to the lever carrying the elevating rope, said elevating rope adapted to rock the main pulley and rock levers and means for clamping and releasing 10 the elevating rope by the rocking movement of the main pulley, substantially as and for the purpose specified.

7. In a hay carrier of the class described, a frame adapted to travel upon a track or way, 20 a pulley carried by said frame, rock levers carried by the frame, said pulley mounted upon an axle carried by said rock levers, a lever located below the rock levers, an elevating rope suspended from the last mentioned 25 lever, said elevating rope adapted to actuate said lever in a downward direction and the rock levers adapted to actuate said lever in an upward direction, and means for clamping the rope by the down pull of the lever carrying 30 the elevating rope, substantially as and for the purpose specified.

8. In a hay carrier of the class described, a frame adapted to travel upon a track or way, said frame provided with rock levers, a main 35 pulley carried by said rock levers, a lever located below said rock levers and main pulley, a pivoted catch carried by said last mentioned lever, a fixed rib or bar adapted to engage said catch, an elevating rope connected to 40 said catch and suspended by the lever, said elevating rope extended downward and carrying a load elevating device, thence upward and over the main pulley and means for releasing and clamping the elevating rope by 45 the simultaneous rocking movement of the rock levers and main pulley, substantially as and for the purpose specified.

9. In a hay carrier of the class described, a frame adapted to travel upon a track or way, 50 said frame provided with rock levers, a main

pulley carried by said rock levers, a lever located below said rock levers and main pulley, a pivoted catch carried by said last mentioned lever, a fixed rib or bar adapted to engage 55 said catch, an elevating rope connected to said catch and suspended by the lever, said elevating rope extended downward and carrying a load elevating device, thence upward and over the main pulley and means for releasing the clamping and elevating rope by 60 the simultaneous rocking movement of the rock levers and main pulley, and an auxiliary catch, substantially as and for the purpose specified.

10. In a hay carrier of the class described, 65 an upper frame provided with traveling wheels adapted to travel upon a track or way, a lower frame fixedly clamped to the upper frame, said lower frame provided with rock levers adapted to oscillate in a plane transverse to the track or way, a main pulley carried by said rock levers, said pulley rotating about an axis parallel with said track or way, a lever located below said rock levers, one end of said lever being in operative engagement with the rock levers, a fixed rope grip and a movable rope grip, the said movable rope grip actuated by the movement of the 70 said lever, an elevating rope connected to said lever, said elevating rope extending downward and carrying a load elevating device, thence upward between the rope grip and over said main pulley and means whereby 75 the elevating rope is clamped between said rope grip by the operation of the weight of the load upon the said lever and means whereby the said rope grips are separated and the rope unclamped by the operation of the elevating rope upon said main pulley and rock levers, when a pull is given upon said 80 elevating rope in a direction adapted to elevate the load, substantially as described.

In testimony that I claim the above, I have hereunto subscribed my name in the presence of two witnesses.

MATHIAS THURSTON.
